UNITED STATES PATENT OFFICE.

TIMOTHY LYDON, OF BALTIMORE, MARYLAND.

WALL AND CEILING STRUCTURE.

Application filed January 19, 1922. Serial No. 530,325.

To all whom it may concern:

Be it known that TIMOTHY LYDON, a citizen of the United States, residing at Baltimore, in the State of Maryland, has invented certain new and useful Improvements in Wall and Ceiling Structures, of which the following is a specification.

This invention relates to improved means for securing tiles, slabs or plates in place in the formation of ceilings or walls.

The term tiles as herein employed by me is used in a broad sense in that it is applied by me to any wall or ceiling element which is molded or shaped into a tile, slab or plate and is not necessarily a baked product.

The object of the invention is to provide improved means whereby tiles, slabs or plates may readily be secured to overhead joists to form a ceiling or to studding in the formation of a wall,—the structure being such that unskilled labor may be employed and the tiles readily applied regardless of the irregularity in the spacing of the joists or studding.

With the above and other objects in view the invention is illustrated in the accompanying drawings, wherein,—

Fig. 1. shows a sectional perspective view of a series of joists with flooring on the upper side and with my improved tile securing devices on the lower side thereof.

Fig. 2. illustrates a cross-sectional view of the same,—the section being taken on the line 2—2 of Fig. 1 to which the facing slabs have been added.

Fig. 3. shows, in perspective, a series of tile supporting strips and tiles sustained thereby as viewed from the upper side,—the joists above being omitted.

Fig. 4. illustrates a side edge view of a plurality of tiles to show how they lap.

Fig. 5. shows an enlarged detail of one of the tile supporting strips with a tile at each side thereof and also shows the means for securing the strips in place.

Fig. 6. illustrates one of the detached tile-supporting strips.

Fig. 7. shows one of the tiles in perspective.

Fig. 8. illustrates a sectional detail through the tile, in a lengthwise direction or from end to end, and

Fig. 9. shows a cross-sectional detail

through the tile from one side edge to the other.

Referring to the drawings the numeral 12, designates a series of spaced-apart supports such as joists or, in the case of a wall, a series of studs which in practice are presumably spaced at equal distances apart, but in reality are frequently spaced unequally. In some instances the unequal spacing between the centers of the joists or studs is so pronounced that it is impracticable to attach tiles, slabs or plates directly to those joists or studs, but in accordance with my invention it is immaterial whether the joists or studs be equally or unequally spaced.

In carrying out my invention I employ what I term a series of supporting strips or rails 13. These strips or rails as best shown in Fig. 6 of the drawings have flat parallel inner and outer faces 14 and 15 respectively,—the outer face being wider than said inner face so as to form longitudinal side flanges 16 at opposite sides of each strip.

The supporting strips or rails 13, are seated with their inner narrower faces 14 against the joists or studs and extend at right angles to the latter so that each strip will extend across a series of joists or studs, as clearly shown in Fig. 1 of the drawing.

These strips or rails 13 are equally spaced and are rigidly secured to the joists or studs they cross by means of nails or equivalent fastenings 17, as shown in Fig. 5 of the drawings.

In some instances I have found it desirable to lay a brace strip 18, against the outer wider face 15 of each rail 13 and have the fastening 17 extend through the latter, then through the rail and onto the joist or stud 12. This brace plate by extending across the outer wider face of the rail serves to support the rail at the opposite edges where the side flanges 16 are located, which is very desirable as will presently be seen.

In the case of a ceiling structure the upper side of the joists will sustain the flooring 19 as shown in Figs. 1 and 2.

In carrying out my invention I utilize a special construction of tile, slab or plate, 20, a form of which is shown in Figs. 7-8 and 9 of the drawings to which attention is now directed.

For the sake of brevity I shall herein-

after make use of the single expression slab, which however is to be construed as meaning a comparatively thin tile, slab or plate.

Each slab 20 has an inner surface 21 and an outer surface 22.

At each side the slab is provided with an overhanging flange 23 while at one end there is a flange 24 that is flush with the inner surface 21 and which projects beyond the outer surface 22. At the opposite end, the slab has a flange 25, which is flush with the outer surface 22 and which projects beyond the inner surface 21.

By reference to Figs. 7-8 and 9 it will be noted that the flanges 23-24 and 25 are each half the thickness of the slab so that if an underlapping flange 25 on one end of a slab is fitted against an overlapping flange 24 on the end of another slab the two lapped flanges will together substantially equal the thickness of a slab.

By referring to Figs. 8 and 9 it will be noted that each slab has a plurality of wire strands 26 extending crosswise therethrough and that the opposite ends of the wire strands project along the under faces of the side flanges 23, all for a purpose presently to be explained.

The supporting rails or strips 13 are so spaced with respect to each other that a slab 20 may be placed between them with the side flanges 23 of the slab lapping the side flanges 16 of the rails, as clearly shown in Figs. 3 and 5 of the drawings.

In the case of a ceiling structure the flanges 23 of the slab will seat in the flanges 16 of the rails at opposite sides of it and thus sustain the slab between the two rails.

It will also be noted that as the ends of the cross-wires 26 project along the under side of the slab flanges 23 that they will reinforce those flanges at the point of suspension.

As the weight of the slabs is directly on the rail flanges 16 any tendency of those flanges to split or break off is overcome by the brace strip 18.

By reference to Fig. 5 it will be noted that when the slabs are seated on the rail flanges 16 their inner faces 21 will be slightly spaced from the lower faces of the

joists 12,—this space being desirable in a ceiling structure inasmuch as I usually slide the slabs between the rails 13 when hanging them in place.

After the slabs are in place they may be painted or may be covered with a plaster finish,—this however being immaterial to my invention.

When the slabs are in place their ends will be engaged by the end flange 24 of one lapping the end flange 25 of the next so that an end support will thus be provided between the ends of abutting slabs.

Having described my invention, I claim,— 65

1. In a wall or ceiling structure the combination with spaced apart supports of parallel but spaced-apart flanged rails extending at right angles to and crossing said supports said rails being rigidly secured 70 against the said supports, separate slabs each having overhanging side flanges at two opposite sides and each slab also having at one end a flange that is flush with the inner surface of the slab while at the opposite end each slab has another flange which is flush with the outer surface of the slab whereby to produce an underlapping flange at one end and an overlapping flange at the opposite end of said slab,—the slabs being 80 supported by their side flanges on the flanges of the rails and one end of a slab underlapping the slab next to it at that end while the opposite end of the same slab will overlap the slab next to it said latter 85 end and the adjacent ends of two slabs thereby be brought into direct butting and lapping contact one with the other.

2. The combination with spaced apart supporting means, of flanged rails secured 90 to said supporting means and extending crosswise of the latter, separate slabs each having side flanges which engage and are sustained by the rail-flanges and said slabs also having an underlapping flange at one 95 end and an overlapping flange at the opposite end whereby the adjacent ends of the several slabs may be lapped and supported at the end one by the other.

In testimony whereof I affix my signature. 100

TIMOTHY LYDON.
